UNITED STATES PATENT OFFICE.

ALEC BROWETT, OF 161 Highbury Hill, County of Middlesex, England.

APPARATUS FOR SEPARATING, DAMPING, AND FIXING POSTAGE-STAMPS, &c.

SPECIFICATION forming part of Letters Patent No. 340,856, dated April 27, 1886.

Application filed March 18, 1885. Serial No. 159,349. (No model.) Patented in England February 12, 1885, No. 1,976; in France February 18, 1885, No. 167,131; in Belgium February 19, 1885, No. 67,931, and in Germany February 24, 1885, No. 32,382.

To all whom it may concern:

Be it known that I, ALEC BROWETT, engineer, a subject of the Queen of Great Britain and Ireland, and residing at 161 Highbury Hill, in the county of Middlesex, England, have invented certain Improvements in Apparatus for Separating, Damping, and Fixing Postage-Stamps or other Labels, (for which I have obtained British Patent No. 1,976, dated February 12, 1885; French Patent No. 167,131, dated February 18, 1885; Belgian Patent, No. 67,931, dated February 19, 1885, and German Patent No. 32,382, dated February 24, 1885,) of which the following is a specification.

15 My invention has for its object to provide a simple and convenient apparatus for separating postage-stamps or other labels singly from a sheet or strip, damping the same, and affixing them onto letters or other surfaces.

20 I will describe my invention with reference to the accompanying sheet of drawings, Figure 1 of which is a plan of the table or platform of the apparatus upon which the sheet or strip of stamps or labels is placed in position 25 to be separated and damped, as hereinafter described. Fig. 2 is a vertical section of the table, the section being taken along the line 1 2 in Fig. 1, and Fig. 3 is a similar section taken along the line 3 4, Fig. 1. Fig. 4 is a vertical section of the instrument used in conjunction with the said table for effecting the separation of the stamps or labels singly from the sheet or strip, effecting the damping of the separated stamps or labels, and afterward the 30 affixing of them onto letters or other surfaces.

35 Fig. 5 is a vertical section, at right angles to Fig. 4, of the lower portion of the said instrument, and Fig. 6 is a plan of the under side or face of the said instrument.

40 The sheet of stamps or labels is placed on the surface of the table A, with the gummed side downward or next the table, and with the corner stamp or label of the sheet or the end stamp or label of a strip of stamps inserted in 45 a slit or opening, a, provided between the surface of the table and a guide, B, secured thereto, which guide is for the purpose of insuring the stamp or label to be separated being placed in the correct position to be severed by 50 the instrument, Figs. 4, 5, and 6, as herein-

after described. This guide may be formed in one with the cutter C, as shown in my drawings, or it may be made separate therefrom and fixed to the table by any suitable means. The cutting-edge of the cutter extends along 55 two sides of a rectangular parallelogram, as shown in Fig. 1, so as to act upon the two unsevered sides of the corner stamp or label. This cutter is fixed in a recess in the table A, with its cutting-edge level with or slightly below 60 the surface thereof, so as to prevent it from interfering with the feeding up of the stamp or label to be severed from the sheet or strip. Within this cutter is fitted a piece or block of absorbent material or substance, D, (pumice- 65 stone is, I believe, the most suitable substance for the purpose,) the upper surface of which is maintained in a wet condition by capillary attraction, the lower part of the block being immersed in water contained in a trough or 70 reservoir, E, fixed to the under side of the table A and supplied with water through an opening, b, closed by a suitable plug or stopper, c.

The block D is provided with a cylindrical 75 or other passage or chamber, F, in which is fitted to work a piston, G. The face of this piston is normally maintained above the surface of the block D by a spring, d, bearing at one end against the under side of the head of 80 the piston and at its opposite end against a collar, e, fixed in the chamber or passage F, which collar also serves as a guide to the stem f of the piston G. The height to which the piston G is made to project above the block D 85 may conveniently be regulated as desired by a cap, g, screwed more or less onto the stem f, the said cap, in the normal position of the piston, bearing against a nut, h, which holds the cylinder or chamber F in position. 90

The corner stamp or label of a sheet or strip having been placed in position in the guide B, as hereinbefore described, the plunger H of the instrument, Fig. 4, is inserted in the guide B. The edges i of the face of this 95 plunger form a cutting-edge sliding inside and in contact with the cutter C, so as to operate therewith, after the manner of shears, to separate when depressed the stamp or label from the sheet or strip. The stamp or label 100

thus separated from the sheet or strip is by the further depression of the instrument, Fig. 4, pressed against the top surface of the block D, whereby the gummed surface of the stamp 5 is damped. The piston G is by the descent of the plunger H forced into the cylinder F, the spring d being consequently compressed. A passage, k, is formed through the plunger H, communicating with a tubular stem, I, fixed to the rear of the said plunger and having fixed to its upper end a collapsible structure or vessel—such, for example, as a hollow ball or chamber, K, of india rubber or other suitable flexible material inclosed in an outer 10 casing, L—which forms the handle or knob by means of which the plunger H is depressed. This casing is fitted to slide on the tubular stem I, and in or over the correspondingly-formed extension, H', of the plunger, a spring, 15 M, being interposed between the said plunger and the casing L, which tends to separate them from each other.

When pressure is exerted upon the knob L for the purpose of separating the stamp or label 20 from the sheet or strip and of pressing it onto the damping-block D, the casing is caused to slide on the tubular stem I and cylindrical portion H' of the plunger, whereby the flexible ball or chamber K and the spring M are 25 compressed and the air contained in the flexible chamber is forced therefrom through the tubular stem I, and passage k, in the plunger, thence through the branch passage k', and past the spring-valve k². When pressure is removed from the plunger and the plunger raised 30 from the block D, the vacuum caused or suction exerted by the tendency of the collapsible vessel or ball K to return to its original position will cause the damped stamp or 35 label to adhere to the plunger, the removal of the damped stamp or label from the block D being facilitated by the simultaneous rising of the piston G by the expansion of the spring d. The plunger, with the damped stamp or 40 label adhering thereto is then removed from the guide B and pressed upon the letter or other surface to which the stamp or label is to be affixed. The pressure exerted upon the 45 knob K for this purpose will cause the vacu-

um or power of suction previously formed to 50 be destroyed by admitting air through the valve k², and thus the stamp or label will be released from the surface of the plunger, which stamp will then adhere to the surface against which it was pressed. 55

7 are passages communicating with the recess in the table in which the plunger slides, to allow the air to escape as the plunger H descends therein for the purpose of damping the stamp. 60

I do not limit myself to the precise details hereinbefore described, and illustrated in the accompanying drawings, as it will be evident that they may be varied within considerable limits without departing from the nature of 65 my invention.

I claim—

1. The combination of the table carrying a cutter and a moistening block, with a corresponding plunger constructed to cause the 70 stamps or labels to adhere to the plunger, substantially as set forth.
2. The combination of a plunger constructed to cause the stamp to adhere thereto, with a table carrying a cutter and a moistening-block, and a guide, B, overlying the cutter to facilitate the separation of the stamp from the sheet on the withdrawal of the plunger with the adherent stamp. 75
3. The combination of a plunger constructed 80 to cause the stamps to adhere thereto, with a table carrying a cutter, a guide B, and a spring-plunger, G, to facilitate the separation of the stamp.
4. The combination of a plunger constructed 85 to cause the stamps to adhere thereto, with a table having a capillary moistening-block, D, spring-plunger G, and cutter, substantially as described.

In testimony whereof I have signed my name 90 to this specification in the presence of two subscribing witnesses.

ALEC BROWETT.
